COIN CONTROLLED MECHANISM FOR
VENDING MACHINES

Louis H. Morin, Bronx, N. Y., assignor to The
Coca-Cola Company, Wilmington, Del., a cor-
poration of Delaware

Application July 22, 1936, Serial No. 91,836

1 Claim. (Cl. 194—85)

This invention relates to vending machines and particularly to the mechanism employed for controlling the coin operation of machines of this kind to render such machines substantially fool-proof in operation; and the object of the invention is to provide a mechanism of the class described employing a coin controlled coupling for placing the crank or manually actuated member in operative engagement with the shaft or other member to be driven; a further object being to provide a coupling device involving an intermittently rotated disk having a plurality of circumferentially spaced sockets in which a coin is adapted to pass, and with pawls adjacent said sockets adapted when in operative position to retain said disk against rotation in one direction and an oscillatory coupling segment for engaging the coin to feed said disk intermittently; a further object being to provide means involving a plurality of control elements for rejecting and returning improper coins or slugs introduced into the machine, one of said elements being in operative engagement with an "empty" control device to eject or return a proper coin when the machine is empty of the articles to be dispensed thereby; a further object being to provide means on the crank or manually actuated shaft of the mechanism for limiting the movement of said crank in two directions; a still further object being to provide means in direct operative engagement with the crank shaft for cushioning the movement of said shaft in both directions so as to render the operation thereof substantially noiseless; and with these and other objects in view, the invention consists in a mechanism or apparatus of the class and for the purpose specified, which is simple in construction, efficient in use, and which is constructed as hereinafter described and claimed.

The invention is fully disclosed in the following specification, of which the accompanying drawings form a part, in which the separate parts of my improvement are designated by suitable reference characters in each of the views, and in which:

Fig. 1 is a side view of the upper end portion of a vending machine diagrammatically illustrating the attachment of the coin mechanism therewith.

Fig. 2 is a sectional view through the casing of the mechanism substantially on the broken line 2—2 of Fig. 3.

Fig. 3 is a section on the line 3—3 of Fig. 2

showing parts of the construction broken away. Fig. 4 is a section on the line 4—4 of Fig. 2.

Fig. 5 is a section on the line 5—5 of Fig. 2; and, Fig. 6 is a section on the line 6—6 of Fig. 2, with parts of the construction broken away. 5

In Fig. 1 of the drawings, I have diagrammatically illustrated at 10 the upper end portion of a cabinet or frame of a vending machine, particularly designed to vend bottles 11 through an opening formed in the top of the cabinet at the 10 place designated at 12. Supported upon the top of the cabinet 10 is a base casing or housing 13 upon which the case 14 of the coin controlled mechanism is mounted.

The case 14 includes a removable cover 15 controlled through a key lock 16 to gain access to the interior of the case for the removal of coins from the coin receiving receptacle 17 in said case or for the purpose of making repairs or alterations. At 18, I have shown the coin admission 15 opening, forming part of a coin jumper box 19, which controls transmission of a coin into and through a coin guiding track or housing 20 suitably supported in the interior of the case 14 and having a coin admission track 21 and a coin discharge track 22, the latter opening into a return trough or receptacle 23 formed in the cover 15. At 24, I have shown a window or opening arranged in the cover and in conjunction with which a signal flag 25 having the word "Empty" 30 thereon is adapted to operate.

The bottles are supported and operated in the cabinet 10 by means of a suitable conveyor represented diagrammatically by the dotted lines 26 in Fig. 1 of the drawings and which is more fully shown and described in a companion application Serial No. 91,837, filed July 22, 1936, allowed September 15, 1938. This conveyor is intermittently rotated through a tubular drive shaft 27 manually actuated through a crank shaft 28 mounted 40 in one side wall of the case 10 as clearly represented in Fig. 2 of the drawings, the shaft having an extending crank arm 29 with a knob or finger piece 30, by means of which the same may be rotated. 45

The case 14 has an inner supporting wall 31 having a downwardly extending bearing portion 32 in which is rotatably mounted a coin disk 33 or the downwardly extending sleeve portion 34 50 thereof, the latter having an angular bore 35 to receive the angular or square end 27a of the tubular shaft 27.

The disk 33 forms part of a coin controlled coupling and drive unit which includes a drive 55

segment 35 and a disk or ring 36. The segment 35 includes a beveled gear segment 37 in connection with which a drive beveled pinion segment 38 operates. The pinion 38 is actuated through a drive lever 39 secured to the crank shaft 28 and coupled with the pinion 38 through a shearing pin 40, the latter providing a breaking point which will avoid undue stresses and strains on the several parts of the coin mechanism should the same become jammed or tentatively rendered inoperative for any reason. Secured to the shaft 28 is a pinion gear 41 in connection with which a gear segment 42 operates, the latter being pivoted to the cylinder frame 43 as seen at 44. The frame 43 is arranged upon the shaft 28 and supported in the case 14, and includes a piston cylinder 45 in which a piston 46 is adapted to operate. A connecting rod is shown at 47 for coupling the piston 46 with the projecting arm 48 of the gear segment 42 so that the rotation of the shaft 28 may be transmitted to said piston, the latter acting as a check to control the rotation of the shaft by the crank 29 in both directions.

The piston 46 is checked in its movement in one direction by a coil spring 49 seating upon the piston and an adjustment nut 50, the latter being employed to control the spring tension, whereas the movement of the piston in the opposite direction is controlled by a restricted discharge orifice 51 in the cylinder, restricting the discharge of the air therefrom to produce a substantial dash-pot action. Air is admitted into the cylinder 45 through a check valve 51a supported in connection with a plug or head 52 mounted in the end of the cylinder. The plug or head 52 has an annular groove 53 in conjunction with which the lock element 16a of the key lock mechanism 16 operates, to retain the cover 15 in position as clearly seen in Fig. 5 of the drawings. The beveled pinion 38 has an offset stop arm 38a which limits the rotary movement of the shaft 28 in one direction, whereas the drive lever 39 has a similar offset stop arm 39a which limits the rotary movement of the shaft 28 in the opposite direction. The crank 29 is free to swing through an arc of 180°, during which operation, the drive segment 35 is rotated through an arc of 90°.

The segment 35 includes an upwardly extending semi-circular cam portion 54 which cooperates with a coin check lever 55 pivoted to the housing 20 as clearly seen in Fig. 2 of the drawings and having a projecting tongue or finger 56 extending through the housing and arranged in position to check the transmission of a coin through the discharge track 22a, for admission into the coupling element as will be clearly seen upon a consideration of Fig. 3 of the drawings, it being apparent that as cam portion 54 moves with segment 35 upon actuation of the device, said cam causes check lever 55 to move into a position approximating the vertical, finger 56 thereof then closing the coin tract so as to preclude introduction of further money into the coupling assembly until such time as such has been returned to an initial position where such reception is contemplated. Detachably secured to the segment 35 is a coin engaging block or coupling element 57 which is adapted to engage a coin dropped into position in the coupling device as indicated at 58 to cause the disk 33 and the ring 36 to be rotated and to correspondingly rotate the shaft 27.

The ring 36 is provided with four equally and circumferentially spaced coin receiving hoppers

59 into and through which coins are adapted to pass from the discharge track 22a when one of said hoppers is disposed in registering alignment therewith. The disk 33 is also provided with apertures 60 in registering alignment with the hoppers 59 to permit the coins to drop into engagement with the disk 33 and onto the upper surface of the transverse partition wall 31 of the case. One end of each of the apertures 60 is enlarged as indicated at 61 and these enlarged portions open outwardly through the peripheral edge of the disk 33 as may be seen in Figs. 5 and 6 of the drawings. Pivottally mounted on pins 62 supported in the disks 33, 36 are coin engaging pawls 63, one end 64 of which extends into the aperture 61 to engage the coin 58 and also to be engaged by a spring pressed plunger 65 which serves to normally project the other end 66 of the pawl outwardly so that when the pawl is in the position shown at the right of Fig. 6 of the drawings, the pawl will engage a stop block 67 on the case to prevent backward rotation of the coupling device. Whereas, when the segment 35 is rotated, the block 57 moves the coin 58 in the direction of rotation and draws the end portion 66 of the pawl inwardly in the operation of rotating the coupling device and moving the coin including the pawl 63 engaging the same 90°, during which operation, one of the bottles 11 will be advanced and projected through the cabinet 10 by the rotation of the shaft 27 and the endless conveyor and feed 26 driven thereby. A projected bottle is indicated at 11a in Fig. 1 of the drawings.

In this connection, it will be understood that each quarter portion or area of the periphery of the disks 33, 36 is of the same construction, and when one quarter section or area has been moved from the position shown at the right of Fig. 6 into the position shown at the bottom of Fig. 6, the section at the top of Fig. 6 is moved into the position at the right of Fig. 6. This operation continues intermittently as each coin is introduced into the machine and drops into the hopper 59 and aperture 60 of said disks.

After the first cycle of operation, above described, the coin 58 remains in its supported position upon the partition wall 31, but in the next cycle of operation, the coin will drop into the pan or receptacle 17 through an elongated slot or opening 31a formed in the wall 31 as will be clearly seen upon a consideration of Fig. 6 of the drawings. This operation or movement of the coin is assisted by the engagement of the coin with a cam or beveled surface 35a of the segment 35, as will be seen in the side elevation of said segment as represented in Fig. 2 of the drawings. The contour of the pan or coin receiving tray 17 will be understood upon a consideration of Figs. 2, 3, 5 and 6 of the drawings. If a coin is not disposed in the hopper 59 and aperture 60, the segment 35 will be free to oscillate back and forth within and between the disks 33 and 36 without transmission of any rotary movement thereto or to the shaft 27.

Several means are provided to control and regulate the transmission of a proper coin into and through the mechanism of the machine, for example, the jumper box 19, which is old in the art and controls the transmission of the coin from the slot or admission opening 18 into the guide track or housing 20, or the channels or tracks 21, 22, 22a thereof. A triangular magnet 68 is arranged centrally of the housing 20 and is exposed to the tracks or channels 22 to draw a

magnetically influenced coin from the track 21 downwardly into the track 22. The check lever 55 forms another control as previously described. A coin return lever 69 pivoted to the housing 20 as seen at 70, constitutes another control in the form of a weighted member which will swing on its pivot when engaged by a coin of the proper weight to permit transmission into the discharge track or channel 22a, but, on the other hand, will 10 guide a light coin into the track or discharge channel 22. In connection with the lever 55, it will be understood that when the segment 35 is in operation, another coin is not permitted to enter the track 22a.

15 I have also provided means to prevent the admission of a coin into the track 22a when the machine or cabinet is empty, or, in other words, does not have a bottle 11 in position to be vended. This control consists of a lever 71 pivotally supported in the cabinet 10 as indicated at 72 and provided with an upwardly extending cam portion 73 adapted to be normally depressed by a bottle 11 when in position in the cabinet. The other end 74 of the lever is weighted to move the 25 end 73 into raised position when a bottle does not prevail in the position represented at 11b, in Fig. 1, so that a rod 75 coupled with the end 74 of the lever will be held down so that the end 75a of said rod, note Fig. 3, will hold the lever 30 69 in its downwardly extended position as shown in full lines in Fig. 3 of the drawings, to prevent the coin from entering the discharge 22a. The offset 75a on the rod 75 is shown in its raised position in Fig. 3, illustrating the ability of the 35 lever to swing freely into the position shown in dotted lines in said figure in the normal operation of the machine. Coupled with the upper end of the rod 75 which extends upwardly through the shaft 27 is a radially extending arm 76 having a cam portion 77 adapted to register with a spring pressed pin 78 supported in a suitable bearing 79 on the housing 20. With this construction, when the rod 75 moves downwardly, the cam 77 operates to move the pin 78 against the tension of the spring 80 thereon to project the pin into the coin slot at 81 to cause a coin to drop through the jumper box 19 directly into the return trough 23. On the bearing 79 is a projecting arm 82, to which is pivoted, 40 as seen at 83, the flag element 25 which forms part or one end of a lever, the other end of which is coupled with the pin 78 and is moved therewith to move the flag 25 from the position shown in full lines in Fig. 4 into the dotted line position 45 of said figure, or into registering alinement with the panel or window 24 so that the word "Empty" arranged on the flag 25, note Fig. 2, will be visible through the window 24. When the rod 75 is in raised position, the flag 25 assumes its full line position shown in Fig. 4, and when in lowered position, the flag assumes the dotted line position.

40 The operation of the machine will be readily understood from the foregoing description when taken in connection with the accompanying drawings and the following brief description. The crank 29 will normally assume a rearwardly extending position at the left of the machine as seen in Fig. 4. If a proper coin is now inserted into the aperture 18 and passes downwardly through the tracks or slots 21, 22a, and drops into the hopper 59 and aperture 60 in registering alinement therewith, the crank 29 may then be rotated forwardly, in which operation, the block 57 will engage the coin 58, the latter completing the coupling between the segment 35 and

the disks 33, 36. The beveled pinion 38, engaging the gear segment 37, will cause the disks 33, 36 to be rotated, and the shaft 27 correspondingly rotated to discharge a bottle from the cabinet as previously stated. In this operation, the gear segment 42 will be rotated through the pinion 41 and the piston 46 will be drawn inwardly in the cylinder 45 in the manner illustrated in Fig. 5. The forward rotary motion of the crank 29 is checked by the spring 49. When the crank 29 is released by the operator, the spring 49 will cause the same to return to normal position, which operation is checked by the dash-pot action of the piston in the cylinder as previously described. Thus, both operations of the crank 15 are substantially cushioned to render the crank operation noiseless as well as to eliminate undue stress or strain thereon. The return movement of the crank 29 will also cause the segment 35 to be moved into its normal position and likewise return element 57 in position to engage the next coin introduced into the machine.

20 During the second cycle of operation of dispensing a bottle, the first coin introduced into the machine will be discharged through the 25 aperture 31a into the receiving pan or tray 17. This operation will continue until all of the bottles have been disposed from the machine, and by proper replacement of the bottles in the cabinet 10, this operation will continue indefinitely. The coins are removed from the tray 17 by an authorized agent having a key 16b for actuating the lock 16 which controls the release of the cover plate 15.

30 While I have shown my improved coin mechanism as applied, diagrammatically, to a particular type of merchandise or storage cabinet of merchandise in the form of bottles, this mechanism is applicable for use in conjunction with other kinds and classes of vending machines or 35 articles of merchandise to be vended. The distinctive features of the present invention reside in the simple and substantially fool-proof coupling device employed for operatively uniting the driven member 35 with the combined member 40 45 33-36 to be driven; the various controls for the coin track or channel for ejecting improper coins or elements introduced into the machine; the cushion control of the operating crank and the simple and positive mechanism for actuating the same; the strong and durable structure of the several operative parts and the means employed to couple the crank shaft with the parts to be operated to eliminate breakage through excessive stress and strains, as well as 50 the other features herein set forth. Various changes in the general design and arrangement of the respective parts of the coin controlled mechanism may be made to suit various adaptations and uses thereof in vending merchandise 55 of various kinds and classes.

60 By providing the shaft 27 with the square or angular end 27a, I provide means for quickly and easily assembling and disassembling the coin controlled mechanism with the cabinet of the 65 machine without disturbing any of the mechanisms of the cabinet. In this way, the coin mechanism may be replaced from time to time should the same require repair or alteration, it being understood that new or repair units may 70 be replaced without interfering with the continued operation of the cabinet. This interchanging of the coin mechanism units may be performed as a matter of service in order to check these mechanisms and to maintain the 75

same in proper operative condition at all times, and especially from the standpoint of cleaning the same.

Having fully described my invention, what I claim as new and desire to secure by Letters Patent is:

In a coin controlled mechanism for vending machines, a manually actuated drive shaft, a driven shaft, a coupling device for joining said shafts together to cause the driven shaft to be actuated in the operation of said drive shaft, said coupling device involving a rotary oscillatory segment in direct operative engagement with

the drive shaft, a disk arranged in juxtaposition to said segment and united with said driven shaft, means for supporting a coin in said disk in position to be engaged by said segment to cause said disk to be rotated in the operation of said segment to drive said driven shaft, a pawl pivotally supported in connection with said disk in position to register with and engage a coin supported therein, and a stop block co-acting with said pawl so that when same is in a pre-determined position the disk is retained against rotation in one direction.

LOUIS H. MORIN.
